UNITED STATES PATENT OFFICE.

JOHN H. GILES AND DONALD M. GILES, OF PHILADELPHIA, PENNSYLVANIA.

DRIVE MECHANISM FOR DYEING MACHINES.

Application filed April 19, 1922. Serial No. 555,565.

To all whom it may concern:

Be it known that we, JOHN H. GILES and DONALD M. GILES, both residing at Philadelphia, county of Philadelphia and State 5 of Pennsylvania, have invented certain new and useful Improvements in a Drive Mechanism for Dyeing Machines, of which the following is a specification.

This invention relates to dyeing machines 10 in which yarn in skeins is immersed in a dye liquor. In such machines it is customary to provide a dye vat and a reel, or other device of that character, upon which the skeined yarn may be mounted. The reel is 15 supported so that it may be raised or lowered relative to the dye vat, and when in the lowered position, the lower yarn supporting sticks are below the surface of the liquid. Upon revolving the reel the skeins 20 of yarn are immersed in the dye, and suitable provision is made ordinarily so that all parts of the skein may be subjected to the dyeing action. In devices as thus briefly described, driving mechanism is provided by 25 which the reel may be rotated and it is herein contemplated to provide a new and improved driving mechanism together with means by which the source of power for rotating the wheel may be also utilized to lift 30 the reel clear of the vat.

One of the objects of the invention, therefore, is to provide a new and improved driving mechanism for dyeing machines of the class described, in which means is provided by which the yarn reel may be raised 35 out of the dye vat while being continuously rotated.

Another object of the invention is to provide a new and improved driving mechanism 40 for dyeing machines of the class described, in which the means for revolving the reel may be utilized for raising or lowering the yarn supporting structure relative to the dye vat, provision being made for revolving 45 the reel in either direction of rotation, and at different speeds and the elevating mechanism being operable regardless of such direction.

Other objects and aims of the invention, 50 more or less specific than those referred to above, will be in part obvious and in part pointed out in the course of the following description of the elements, combinations, arrangements of parts and applications of 55 principles, constituting the invention; and

the scope of protection contemplated will be indicated in the appended claims.

In the accompanying drawings, in which there is shown a preferred form of embodiment of our invention:

Figure 1 shows an end view of the dyeing machine provided with our new and improved driving mechanism.

Figure 2 is a side view of the same with part of the enclosing structure removed.

Figure 3 is a detail view with parts broken away of a driving speed changing, and reversing mechanism.

Figure 4 is a detail view on the line 4—4 of Figure 3, showing the various parts used 70 for reversing purposes.

Figure 5 is a cross-sectional view of a detail of the clutch for the elevating mechanism; and

Figure 6 is a view in detail, showing the 75 worm drive for the elevating mechanism.

With reference now to the drawings, in which similar reference characters designate similar parts throughout the various views thereof, 1 designates a dyeing machine having upright supporting members 2, and enclosing plates 3. Mounted on one end of the dyeing machine is the driving mechanism 4 therefor, supported by a suitable bracket 5. The driving mechanism is provided with a 80 pulley 6 mounted in a projecting bracket 7, the pulley 6 being driven from any suitable source of power.

Referring now to Figure 3, it will be seen that the pulley 6 is mounted on the shaft 8, 90 supported in suitable ball-bearings 9 in a case 10. At one end of the shaft 8 there is provided a gear 11, on the inner face of which is mounted a clutch jaw 11^a. The gear 11 meshes with a corresponding gear mounted on the shaft 13, which is also provided with gears 14 and 15 rigidly secured thereto. The gear 14 meshes with a small pinion 16 mounted on the stud 17 in the cas- 95 ing 10 as best shown in Fig. 4, pinion 16 in turn meshing with a gear 18, which is slide- 100 able along a shaft 19, but keyed thereto as indicated at 20. On the inner face of the gear 18 it is provided with a clutch jaw 18^a. It will be seen that the shaft 19 is mounted 105 axially in the inner end of shaft 8, as indicated at 21, but is free to revolve relative thereto. The arrangement of gears and shafts herein set forth is similar to a gear transmission as used in motor vehicles, and 110

it will be seen that in the form of transmission herein shown, it is possible to secure a reverse drive for the shaft 19 by means of causing the gear 18 to mesh with 5 pinion 16 and therethrough to be driven by the gear 14, or to secure a direct drive of the shaft 19 by moving the gear 18 along the shaft until it meshes with the gear 15. By moving the gear 18 further along the 10 shaft until the clutch jaw 18^a meshes with the jaw 11^a, the shaft 19 will be directly driven from the shaft 8, that is to say, there will be no reduction in speed between shaft 8 and shaft 19. By moving the gear 18 to 15 the point in between the gears 14 and 15, it is possible to stop the rotation of shaft 19, and the structure mounted thereupon, as will be later described, while at the same time permitting shaft 8 to be continuously 20 driven.

In order to secure the speed changes by causing the gear 18 to mesh with different gears on the shaft 18, there is provided in case 10 a stud 22, having keyed thereto an 25 arm 23, having a fork 24 in its extremity, which engages in a groove 25 cut in the hub of gear 18. The stud 22 is provided with linkage, as indicated at 26, 27 and 28, which is in turn connected by means of a rod 29 30 to a handle 30 on the front of the machine. By moving the handle 30 it will be seen that the fork 24 will be rocked so as to move the gear 18 from its position as shown in Figure 3, to the point where it will mesh with the 35 gear 15, or until the clutch jaw on the gear will engage with the jaw on the gear 11.

Shaft 19, as indicated in Figure 2, extends from one side to the other of the machine, and is provided with a coupling 31, 40 by which it is connected to another shaft 32. Shaft 32 passes through a case 33 and slidably mounted on the shaft 32 is one of a pair of clutch jaws 34, the jaw 34 being keyed to shaft 32 and revolvable therewith. Corresponding to the jaw 34 is a similar jaw 35 45 mounted on a sleeve 36 on which is keyed a bevel pinion 37 within the case 33. The pinion 37 meshes with a corresponding pinion 38, which drives the shaft 39, the lower 50 end of the shaft 39 being provided with a worm 40, which meshes with a worm wheel 41 mounted on a shaft 42. The jaw 34 is provided with a groove 43 in which engages a fork 44, operable by means of a rod 45, 55 a bell-crank 46, a rod 46^a, and a handle 46^b mounted on the front of the machine, the bell-crank being provided, as is obvious, so as to change the direction of movement of the handle. The rod 46^a is suitably provided with a spring 46^c so that when the handle is operated, pressure must be maintained upon it, in order that the fork 44 60 will continue to hold the jaw 34 in its advanced position. When the handle 46^b is 65 operated, the linked parts will force the jaw

to engage the jaw 35 whereupon the revolution of the shaft 32 will be communicated to the bevel gears and to the shaft 39. The shaft 32 projects through the machine and at its end has a pinion 47 which meshes with 70 a gear 48 driving a shaft 49^m journalled at its other end in a bearing 50. The shaft 49 is located in proximity to the periphery of the yarn supporting reel 51, which as seen, 75 consists of a pair of heads 52—52, the periphery of one of these heads being provided with teeth which mesh with a pinion 53, mounted on the shaft 49.

It will be seen then that as the pulley 6 is 80 rotated, it communicates motion in one direction or the other through the gear-shift to the shaft 19, which in turn drives the shaft 49 and causes the reel to be revolved. The reel 51 is provided with yarn supporting sticks running between the heads in the 85 usual manner, the skeined yarns being supported on these sticks.

As indicated in Figure 2, the reel 51 is in the lowered position in which the lowermost sets of sticks on the reel will pass upon a 90 revolution of the wheel below the surface of the dye liquor, which is contained in a suitable vat in the lower part of the dyeing machine. The heads 52—52 are suitably supported on a shaft 54, which run in bearings 95 mounted in the ends of arms 55, these arms being supported at their other ends on the shaft 49, as shown in Figure 1.

The bearings for shaft 54 are movable in 100 arcuate slots 56 in the end enclosing plates 3 for the dyeing machine, and when the arms 55 are raised in a manner to be described, the shaft 54 with the yarn supporting reel will be elevated to a position so that the lower sticks of the reel are clear of the 105 dye liquid. The means for elevating the reel consists of the parts as follows: The arms 55 have pivoted near their middle points links 57 which are in turn mounted at their other ends on eccentric pins 58 110 mounted in gear wheels 59, the gear wheels being supported on suitable studs in the frame of the dyeing machine, and meshing with pinions 60 mounted rigidly on the ends of shaft 42. When the clutch jaws 34 and 115 35 are engaged, the shaft 39 will be rotated and this will in turn cause rotation of the gear wheels 59. This in turn causes the links 57 to be raised, carrying the arms 55 and shaft 54 therewith.

By reason of the fact that the shaft 55 is 120 moved in an arc about the shaft 49, as a centre, the teeth on the head 52 will continue in mesh with the pinion 53, so that the reel will be rotated at all times, regardless of its 125 position relative to the dye vat, and in the same way the elevating mechanism will operate to raise the reel relative to the dye vat, regardless of the direction of rotation of the reel.

Inasmuch as it is a matter of indifference as to which direction the shaft 59 rotates in throwing the link 57, if by any chance the clutch should not be disengaged when the reel has reached the end of its upward travel, no damage will result, inasmuch as the continued revolution of the gear 59 will draw the crank downwardly, and thereby lower the reel to its operative position, as shown in Figure 1. As a further safeguard, as has been explained, the clutch control rod 46^a is provided with the disengaging spring 46^c, so that whenever the handle 46^b is released, the rod 46^a will be moved so as to disengage the clutch, and thereby stop the movement of the hoisting mechanism.

In order to assist the movement of the reel, there are provided suitable counterweights 61, mounted on pulleys 62 on shafts 63, journaled in the top frame of the dyeing machine, the shaft 63 being connected by a suitable cord 64 with the bearings on the ends of shaft 54.

It will accordingly be seen that we have provided a simple, effective driving mechanism for a dyeing machine, well adapted to produce the desired results and one which will withstand rough and careless usage. In elevating the reel no damage can possibly result if the clutch is not disengaged at the end of the upward or downward movement of the reel, and it is, therefore, not necessary to provide automatic stops, or other devices of that character, by which to limit the vertical travel of the reel. The reel may be rotated in either direction, as convenient, and the elevating mechanism is effective either way.

The gear-shift and clutch mechanism are suitably enclosed so as to be protected, and in turn to protect the operator. While specific arrangements as to the gear-shift, clutch and driving mechanism have been indicated, it will be understood that various modified arrangements can be substituted therefor within the scope of the invention, provided such arrangements will permit the continued rotation of the reel in either direction during its elevation and lowering.

Having thus described our invention what we claim as new and desire to secure by Letters Patent is:

1. In a dyeing machine provided with a dye vat, in combination, a yarn stick supporting reel mounted on a shaft, pivoted arms supporting said shaft the head of said reel having a geared ring concentrically disposed with respect to the said shaft, cranks to throw said arms on their pivots, a gear mounted on one of said pivots and engaging the said gear on said reel, and means to drive said cranks and said first named gear, whereby to shift said reel while rotating it.

2. In a dyeing machine, provided with a

dye vat, a yarn reel rotatable into said vat and having a circumferential gear, a drive shaft therefor reversibly driven and having a gear thereon meshing with the gear formed on the periphery of said reel, a second shaft provided with cranks, supporting arms for said reel pivoted on said drive shaft, and movable by said cranks to shift said reel relative to said vat in a curved path and in constant engagement with the said gear on the drive shaft, and a clutch to control the revolution of said second shaft.

3. In a dyeing mechanism provided with a dye vat, a yarn reel rotatable into said vat, a reversibly driven shaft to rotate said reel, means for transmitting the power of the said shaft to the reel, and means to shift said reel in a curved path and in constant engagement with the said power-transmitting means about said shaft as a pivot, whereby to raise said reel, while being rotated, from said vat.

4. In a dyeing machine, provided with a dye vat, a yarn reel rotatable into said vat and supported in arms, a reversibly driven shaft to rotate said reel, means for transmitting the power of the shaft to the said reel, said arms being pivoted thereon, a second shaft having cranks thereon connected to said arms and adapted upon rotation of said second shaft to oscillate said reel in a curved path and in constant engagement with the said power-transmitting means about said drive shaft.

5. In a dyeing machine, provided with a dye vat, a yarn reel rotatable into said vat, a supporting shaft for said reel movable bodily in a curved path and journaled in swinging arms, a second shaft to drive said reel and having said arms pivotally mounted thereon, a reversibly driven shaft to drive said second shaft, means including cranks to rock said arms, and a clutch to connect said means operatively with said reversibly driven shaft.

6. In a dyeing machine provided with a dye vat, a yarn reel rotatable into said vat, a supporting shaft for said reel movable bodily in a curved path and journaled in swinging arms, a second shaft provided with a pinion meshing with a gear formed on the periphery of said reel, said arms being pivotally mounted on said second shaft, a reversibly driven shaft to drive said second shaft, and a clutch to connect said reversibly driven shaft with crank mechanism including cranks connected to said arms and adapted to be thrown to shift said reel relative to said vat while being rotated.

7. In a dyeing machine provided with a dye vat, a yarn reel rotatable into said vat, a supporting shaft for said reel movable bodily in a curved path and journaled in swinging arms, a second shaft to drive said

4
reel and having said arms pivotally mounted thereon, counterweighting means attached to the extremities of said arms adjacent said first named shaft, a reversible driven shaft to drive said second shaft, means including cranks to rock said arms, and a clutch to connect said means, operable with said reversibly driven shaft.

In testimony whereof, we affix our signatures in the presence of two witnesses.
